ATTORNEY

UNITED STATES PATENT OFFICE

ARCHIBALD A. DUNCAN, OF AKRON, OHIO

TELEPHONE RECEIVER

Application filed February 27, 1928. Serial No. 257,183.

This invention relates to electromagnetic sound reproducing apparatus and particularly to telephone receivers, radio loud speakers and other amplifying, sound reproducing devices of a like character.

Objects of the invention are to provide a receiving apparatus of simple construction which can be economically manufactured and which will reproduce sounds in a clear, distinct manner.

A further object is to provide a sound reproducing apparatus which includes a diaphragm actuated by opposed electromagnetic circuits arranged to utilize the full power of each magnet and to thereby provide means for reproducing sound with considerable volume and without distortion.

Other objects and advantages will be readily apparent from the following description in which reference is made to the accompanying drawings in which I have illustrated a form of the invention, it being understood that the invention is capable of various adaptations and that changes and modifications may be made or resort had to substitutions which come within the scope of the claims hereunto appended.

In the drawings:

Figure 1 is a perspective view somewhat diagrammatic in character illustrating the combination and arrangement of parts employed in carrying out the invention,

Figure 2 is a central, cross sectional view of a telephone receiver constructed in accordance with this invention, the sections of the various parts shown in Figure 1, being taken as indicated by the lines 2-2 shown thereon,

Figure 3 is a similar, sectional view taken as indicated by the lines 3-3 of Figure 1,

Figure 4 is a perspective view showing a modified form of the invention.

The invention will now be described with reference to the particular adaptation thereof illustrated in the drawings, in which like characters of reference are employed to designate like parts as the same may appear in any of the several views: The numeral 5 denotes a casing which may be of any suitable form and is preferably composed of brass or

other non-magnetic material. The casing 5 is exteriorly threaded and a cap or closure member 6 is operatively secured thereon. The numeral 7 denotes a diaphragm which is positioned against the open end of the casing 5 and is secured in place thereon by being engaged by the cap 6. The cap 6 is provided with a suitable threaded opening 8 through which the sound waves may pass or into which may be mounted a horn or other tubular extension.

The numeral 9 denotes a copper plate which is secured to the bottom of the casing 5. An electromagnet 10 is suitably secured to the plate 9 so as to extend from one side thereof to a point approximately central thereof. The magnet 10 comprises a coil 10a of copper which is wound around a soft iron core 10b. The core 10b is secured at the bottom thereof to a soft iron strip 10c. A similar core 10d is secured in an upright position to the strip 10c at a point adjacent the other end thereof and a coil 10e of copper wire is wound around the core 10d. The arrangement is such that the core 10d is positioned in coaxial alinement with the diaphragm 7. The reference characters 10f denote a like strip of soft iron which is suitably secured to the top of the core 10b and projects over the top of the coil 10e in spaced relation thereto. The coils 10a and 10e are wound so that the strip 10f becomes a south pole and the upper end of the core 10d becomes a north pole. The strip 10f is provided at a point adjacent the free end thereof with an opening 10g for a purpose to be hereinafter described. A structure comprising the strips 10c and 10f, the cores 10b and 10d and the coils 10a and 10e comprise a magnetic circuit having a gap 11.

The numeral 13 denotes a core which is wound with or surrounded by an electromagnetic coil 12 which is preferably composed of copper wire. An extension 14 of soft iron is secured to one end of the core 13 and the extension 15 is secured to the other end thereof. A vibratory reed 14a composed of soft iron is secured to the extension 14 so as to extend through the gap 11 of the magnet 10. The free end of the reed 14a extends

over the extension 15 in spaced relation thereto. The structure formed by the core 13, the coil 12 and the extension 14, the reed 14a and the extension 15 forms a magnetic circuit having a gap 16.

- The numeral 17 denotes a stem which is suitably secured to the reed 14a and projects upwardly through the opening 10g in the strip 10f, the upper end of the stem 17 is 10 secured to the diaphragm 7 by means of the nuts 18 or other suitable means. While any suitable winding may be employed, I prefer to wind the coils 10a, 10e and 12 from a single strand of wire which is wound on the core 15 10b to form a south pole of the strip 10f. The winding is continued around the core 10d to complete the coil 10e so as to produce a north pole at the upper end of the core 10d. The wire is then extended to the core 20 13 and it is wound thereon to form the coil 12 having a north pole in the strip 15 and a south pole in the strip 14 and the reed 14a. The ends A1 and A2 of the wire A are secured to suitable terminals and are operatively 25 interposed in a receiving circuit. It will be seen that an intermittent electrical current such as is formed by the ordinary transmitter will flow through the coil 10a and 10b and form a powerful electromagnet and that the 30 vibratory reed 14a is positioned through the gap 11 of said magnet. The same current will pass through the coil 12 forming a second magnetic circuit which will act in conjunction with the first named circuit to vibrate the diaphragm 7. As the reed 14a and the strip 10f are of like polarity, the reed 14a will be repelled from the pole strip 10f. The upper end of the core 10d and the coil 10e 35 being of opposed polarity, the reed 14a will 40 be drawn downwardly toward the core 10d. As the free end of the reed 14a projects over the extension 15, the reed will be drawn downwardly toward said extension. The reed 14a is thus actuated by both the repelling and the 45 attracting forces of the magnetic circuit 10 and is also actuated by the attracting force of the magnetic circuit 12 thereby forming a very powerful movement of said reed 14a. As the post 17 is secured to the diaphragm 7, 50 said diaphragm will be actuated in accordance with the impulses flowing through the wire A.

In a modified form of the invention, the strip 10f and 10d and the cores 10b and 10d 55 may be composed of hardened steel, thus forming a permanent magnetic circuit in addition to the electromagnetic circuit 10.

In Figure 4, I have shown a modified form of the invention in which a permanent 60 horseshoe magnet 20 is employed instead of the electromagnetic circuit 12. The free end of the vibratory reed 20 is not positioned over the north pole 20b of the magnet 20, but terminates in spaced relation thereto forming a gap 21. The arrangement is such that

the magnetic flux will flow straight across the gap 21 without depressing the reed 20a. The magnetic circuit 10 being exactly the same as that shown in Figures 1 and 2 will 70 depress the strip 20a and cause the diaphragm 7 to vibrate in accordance with the impulses flowing through the coils 10a and 10e. In this modification, it is to be understood that the poles of the magnet may be reversed and that such other and further 75 changes may be made as come within the scope of the appended claims.

While I have illustrated and described a particular form of winding and have shown the electromagnets connected in series, it is 80 to be understood that any suitable magnetic circuits or connections may be employed and while I have shown the magnets 10 and 12 connected in the same circuit, one of the magnets may be interposed in a separate 85 power circuit if desired.

Having thus illustrated my invention and described the same in detail, what I claim as new and desire to secure by Letters Patent 90 is:—

1. In a receiver of the class described, a diaphragm, an electromagnet, a vibratory reed forming a pole piece of said magnet, said reed having the end free and arranged to be actuated by energizing said magnet, 95 means operatively connecting the intermediate portion of said reed to said diaphragm and a second magnet, the intermediate portion of said reed operatively interposed between the poles of said second magnet. 100

2. In a receiver of the class described, a diaphragm, an electromagnet, a vibratory reed forming a pole piece of said magnet, said reed extending to a point in close spaced relation to the other pole of said magnet 105 thereby forming a gap, said reed arranged to be actuated by energizing said magnet, means operatively connecting the intermediate portion of said reed to said diaphragm and a second electromagnet having a gap, 110 the intermediate portion of said reed operatively interposed in a gap of said second magnet.

3. In a receiver of the class described, a diaphragm, an electromagnet, a flat vibratory reed forming a pole piece of said magnet, said reed having a free end terminating in close spaced relation to the other pole of said magnet thereby forming a gap, said reed arranged to be actuated by energizing said magnet; means operatively connecting said reed to said diaphragm at a point intermediate the length of said reed; a second electro magnet having a gap, said reed operatively interposed in the gap of said second magnet with said point of connection disposed in said second named gap and means to operatively interpose the first named magnet in a receiving circuit and means to energize the second named magnet. 120 125 130

4. In a receiving apparatus of the character described, a diaphragm, an electromagnet having a flexible pole piece extended to a point in close spaced relation to the other
5 pole thereof, said pole piece adapted to be actuated by energizing said magnet, a stem connecting said reed to said diaphragm, a second electromagnet having a gap, the central portion of the flexible pole piece of the
10 first named magnet operatively positioned in the gap of said second named magnet, means to operatively interpose one of said magnets in a receiving circuit and means to energize the other magnet.
- 15 5. In a receiver of the class described, in combination, a casing, a diaphragm operatively mounted therein, an electromagnet having a flat vibratory pole piece positioned in parallel relation to said diaphragm, said
20 pole piece adapted to be actuated by said magnet, a stem connecting said pole piece to said diaphragm, a second magnet, the said pole piece positioned between the poles of the second magnet and means to operatively
25 interpose the first named magnet in a receiving circuit.

In testimony whereof I have hereunto set
my hand.

ARCHIBALD A. DUNCAN.
